Inventor
By H. H. Clegg Atty.

UNITED STATES PATENT OFFICE.

ROBERT J. NICHOLSON, OF WHEATON, ILLINOIS, ASSIGNOR TO ELMER J. MERCIL, OF OAK PARK, ILLINOIS.

INSULATED ELECTRIC CONDUCTOR.

Application filed March 7, 1927. Serial No. 173,401.

My invention relates to insulated conductors and a method of producing the same.

The insulated conductor of my invention includes a ribbon of insulating material disposed in layers and a conductor of electric current interposed between adjacent layers. In forming the insulated conductor, the ribbon of insulating material is wound into a spiral coil and the conductor of electric current is located between adjacent turns of the coil as the coil is being formed. The conductor of electric current is desirably also of ribbon form either in separate strips preferably located abreast and of arcuate formation in the final product or continuous as is the ribbon of insulating material, the two ribbons being then intertwined in the final product. A terminal or terminals may extend laterally into the conductor into connection with the electric current conducting portion or portions thereof. The conductor of my invention has a wide variety of uses among which is its employment as an insulated bus bar through the insulating portions of which terminals are passed into connection with the electric current conducting portion or portions thereof. These terminals may be in the form of hooks which may suspend anodes in an electroplating bath.

The invention will be more fully explained in connection with the accompanying drawing in which Fig. 1 is a perspective view of one form of conductor; and Fig. 2 is a sectional view on line 2—2 of Fig. 1, on a larger scale.

In producing the insulated conductor, the ribbon of insulation 1 is wound in spiral fashion upon a mandrel which defines the bore 2 of the insulated conductor which is hollow.

After the conductor with its metallic element 12 has been formed, it is provided with terminals 13 extending laterally therefrom and projecting thereinto into connection with the electric current conducting portion or portions 12 of the insulated conductor. Where the conductor is to be employed for suspending anodes in an electroplating bath, its terminals 13 may be of hook formation. As I have

practiced my invention, the holes through the conductors 12 and the holes in the ribbon of insulation that register with these other holes are larger than the terminals where these terminals are surrounded by the conductor and insulating ribbon, tin or solder 14 being poured into the space that intervenes between each terminal and the surrounding ribbon and conductor portions whereby these conductor portions are effectively electrically connected with the terminals. The holes through which each terminal extends desirably occur until the bore 2 is reached, so that the solder or tin 14 may flow into the bore and surround the inner ends of the terminals 13 to form anchoring knobs or bodies 14' thereon.

It will be observed that the conductors 12 are thoroughly encased within insulation so as to be inaccessible to the electrolyte of an electroplating bath when such a conductor is used to support electroplating anodes. The current conducting metallic hooks 13 may be replaced from time to time when they are sufficiently consumed by the acid of the bath.

While the insulated conductor of my invention is of particular use in connection with electroplating equipment, it is obvious that it may have other important uses and the invention is not, therefore, to be limited to any particular use to which it may be put.

Changes may be made without departing from the invention.

Having thus described my invention, I claim:

An insulated conductor comprising a ribbon of insulating material spirally wound into a coil having a hollow bore, an electric current conductor disposed between adjacent turns of the coil, a terminal extending transversely of the insulated conductor into said bore and having electric connection with said electric current conductor, and an anchoring body applied to said terminal and disposed in said bore.

In witness whereof, I hereunto subscribe my name.

ROBERT J. NICHOLSON.
